Inventor
Jacob L. Shroyer,
by *Alexander S. Lunt*,
His Attorney.

UNITED STATES PATENT OFFICE.

JACOB L. SHROYER, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

ELECTRIC HEATER.

Application filed December 22, 1925. Serial No. 77,102.

My invention relates to electric heaters and has for its object the provision of a simple and rugged electric heater which may be adjusted.

5 More particularly my invention relates to electric heaters for various objects of indefinite height under which the heater may be placed and then adjusted as desired. My invention has particular application to electric heaters for coffee percolators and the like.

For a more complete understanding of my invention reference should be had to the accompanying drawing in which Fig. 1 is a 15 vertical sectional view of an electric heater embodying my invention, while Fig. 2 is a fragmentary perspective view of reduced size showing the application of the heater to an electric percolator.

20 Referring to the drawing, in carrying out my invention in one form I provide a base member 10 which is hollow, i. e., it is provided with an internal cavity 11. As shown, the base member is smaller at the top, it 25 being substantially cone shaped and at the apex of the cone it is provided with a threaded vertical bore 12 into which is screwed a threaded tubular member 13 which may be a length of pipe. The tubular 30 member 13 extends upward in a substantially vertical position and it is provided with external threads throughout its entire length so that it may be adjusted vertically by screwing it into or out of the base member. A lock nut 14 is provided for securing it in its adjusted position.

On the upper end of the tubular member 13 is mounted a suitable heating unit 15. This heating unit comprises a disk shaped 40 member 16, made of a suitable heat refractory electrically insulating material, which rests in a substantially horizontal position on a metallic supporting member 17. The supporting member 17 is provided with a threaded 45 central bore 18 into which the upper end of the tubular member 13 is screwed and secured by means of lock nuts 19 and 20 on opposite sides of the supporting member. The upper surface of the insulating member 50 16 is provided with a groove 21 in which a helically shaped resistance conductor 22 is placed. The arrangement of the groove 21 and the resistance conductor in the insulating member 16 is preferably substantially

as described and claimed in Patent No. 55 1,522,206 to Rankin, dated January 6, 1925.

Around the periphery of the supporting member 17 is an upwardly turned flange 23 on the upper edge of which the member 16 rests. By means of this flange a space 24 60 is provided underneath the member 16 through which connecting leads 25, 26 and 27 are led to the resistance conductor. The resistance conductor is preferably in one piece, the leads 25 and 27 going to the ends 65 and the lead 26 being connected to a central point thereof. The leads are passed downward through the tubular member 13 into the hollow base member 10 where connection is made with conductors 28 and 29 leading 70 to a suitable electrical supply circuit. Electrically insulating bushings 30 and 31 are provided at each end of the tubular member, and a bushing 32 is also provided in the base 75 member for the conductors 28 and 29.

By means of the lead 26 leading to a central point of the resistance conductor the connections with the supply circuit may be varied to give different heats. This may be effected by means of a suitable switch 33 of 80 any well known form mounted on the base 10. This switch is operated to various positions by means of a knob 34 and is so arranged that for high heat the lead 26 may be connected to one side of the supply circuit, the leads 25 and 27 being connected to the opposite side, whereby the two halves 85 of the resistance conductor are connected in parallel, while for medium heat the lead 26 and one of the other two leads will be connected to the supply source, whereby one 90 half only of the resistance conductor is connected to the supply source, and for low heat the leads 25 and 27 only will be connected to the supply source, whereby the two 95 halves of the resistance conductor are connected in series.

In Fig. 2 is illustrated one application of my invention, this application being to a coffee percolator. The heater is placed 100 underneath the percolator and the height of the heating unit adjusted as desired by adjusting the tubular member 13 with relation to the base, after which the tubular member 105 is locked by the lock nut 14. A suitable aperture will preferably be provided in the base of the percolator to give access to the switch 33.

While I have described my invention as embodied in concrete form and as operating in a specific manner in accordance with the provisions of the Patent Statutes, it should 5 be understood that I do not limit my invention thereto, since various modifications thereof will suggest themselves to those skilled in the art without departing from the spirit of my invention, the scope of which 10 is set forth in the annexed claim.

What I claim as new and desire to secure by Letters Patent of the United States is:

An electric heater comprising a hollow base provided with central and side apertures, a tubular member threaded in said central aperture so as to be vertically adjustable relatively to said hollow base, a circular supporting member provided with a peripheral upwardly turned flange and a 20 central aperture, said tubular member being

threaded to said circular supporting member in said aperture, a lock nut threaded on said tubular member for engagement with said circular supporting member, a disk-shaped heat refractory support resting on 25 said flange in spaced relation with said supporting member, a heating resistance conductor mounted on said heat refractory support, connecting leads extending through a side aperture in said base upward through 30 said tubular support and through the space between said heat refractory support and said supporting member to said resistance conductor and a switch for said heating conductor mounted on said base member and included in said leads.

In witness whereof I have hereunto set my hand this 19 day of December, 1925.

JACOB L. SHROYER.
